UNITED STATES PATENT OFFICE.

HENRY C. MILLER, OF MILWAUKEE, WISCONSIN.

FLEXIBLE BINDER-POST FOR LOOSE-LEAF BOOKS.

1,247,438.

Specification of Letters Patent. Patented Nov. 20, 1917.

Application filed May 22, 1916. Serial No. 99,121.

To all whom it may concern:

Be it known that I, HENRY C. MILLER, a citizen of the United States, and resident of Milwaukee, in the county of Milwaukee and State of Wisconsin, have invented certain new and useful Improvements in Flexible Binder-Posts for Loose-Leaf Books; and I do hereby declare that the following is a full, clear, and exact description thereof.

10 The present invention relates to new and useful improvements in flexible binder posts, for loose leaf books of the general type embodied in Patent No. 1,072,867 granted to me Sept. 9, 1913.

15 It is primarily the object of the present invention to provide a sheathing for the entire body portion of a flexible binder post which is of metal or other essentially non-pliable material presenting a hard smooth 20 surface to the edges of the leaf apertures whereby the manipulation of the leaves with respect to the posts is facilitated, and which includes portions so connected as not to interfere with free flexure of the posts.

25 Flexible posts of the present nature usually comprise a resilient strip normally holding the posts against curvature, and in view of the fact that such spring strips are liable to breakage, it is further an object 30 to provide an arrangement whereby upon possible breakage of the strips, the general assembly of the various parts of the posts will not be affected so that the post may continue to serve its normal function in the 35 book, with the exception of its spring action.

The essential feature of the present invention is the provision of a series of oblong sheathing bands surrounding the body of 40 the post and hingedly connected whereby to permit the normal flexure of the post. This hinged connection of the bands may be procured either by their positioning about the flexible body member, or by pivots connecting the bands and numerous variations of structure may be procured.

In the accompanying drawing several types are shown, each embodying, however, the essential feature of hingedly connected 45 transverse series of sheathing loops disposed about a longitudinal body portion of the post.

Figures 1 and 2 show side and edge views respectively of a binder post provided with 50 transverse sheathing bands which are

hingedly connected by their positioning upon the body member of the post.

Fig. 3 is a view of another type of structure including sheathing bands connected by pivot pins.

Fig. 4 shows a type of post somewhat similar to the structure of Fig. 3 but wherein a more solid formation of the bands is procured.

Fig. 5 shows a form of post somewhat similar to the post of Figs. 1 and 2.

Fig. 6 is a transverse sectional view through this post on the lines 6—6 of Fig. 5.

Fig. 7 is a view showing still another form of post wherein the sheathing bands are formed by a coiled strip.

Fig. 8 is a transverse sectional view through this post on the line 8—8 of Fig. 7.

Referring now more particularly to the structure of Figs 1 and 2, the post therein shown comprises end sheathing bands 5, formed of plates bent in U-shape to embrace the ends of the post body, which in this instance comprises an intermediate metal strip 6 and side filler strips 7 of leather or other slightly extensible material, rivets 8 securing the ends of the post within the plates. The sides of the plates are directed inwardly to form the edge wall portions of the bands, and the ends of these wall portions at the bights of the plates are apertured to provide the usual end channels 9 of the posts which receive the pintle-rods of the book body. Disposed between the end bands 5 are a series of sheathing bands 10 of oblong cross-section to correspond to the cross-section of the post body and the adjacent ends of these bands and of the end bands 5, are oppositely beveled and lapped whereby to present a substantially continuous smooth surface 95 facilitating manipulation of the loose leaves with respect to the posts. To facilitate relative pivotal movement of the bands the end edge portions of the bands are rounded for mutual pivotal sliding engagement, the rounding of certain end edge band portions being procured by convexly extending the end edges to fit in concavely cut away end edge portions of other bands.

Thus the post may be flexed to either side 105 and the smooth surface afforded by the sheathing bands will be substantially retained. In the present structure the hinged connection of the loops is procured by their disposal on the flexible body, although as 110

will be shown in other forms of posts, other hinged connections may be procured. Should the spring strip 6 break, it will be noted that the leather strips 7 which are riveted to the end bands will serve to retain the normal assembly of the posts, so that it may still serve its general function, the intermediate bands being retained on the post by abutment with the end bands.

10 Taking up now the type of post shown in Fig. 3, there are provided intermediate sheathing bands 11, a central sheathing band 12, and end sheathing bands 13. For receiving the pintle rod of the book body, the outer end edge portion of each end band 13 is provided with alining openings 14. The inner side portions of these end bands, together with the side portions of the central band 12 are intermediately cut away as at 15. 15. Disposed transversely in each band 11 is a looped plate 16 having its end portions extended past the sides of the band, and intermediately cut away at 17. When the bands are placed together, the cut away portions 17 of the loop members together with the cut away portions of the bands 12 and 13 provide a transverse space through the post structure whereby a tool member may be inserted to permit a proper heading of rivets 18 passed through the outer end portions of the loops 16 and through the adjacent end portions of the bands 12 and 13. The loops 16 are secured in their respective sheathing bands by transverse rivets 19 passed therethrough, and thus the bands are hingedly held in assembled relation. Extended longitudinally through the series of loops thus connected is a spring strip 20 which is frictionally held by engagement in the loops 16, 20 it being observed that these loops serve to a considerable extent as body filler portions for the posts, although in the present instance the body proper of the post is construed as the spring strip 20.

45 The form of post shown in Fig. 4 embodies sheathing band members which, however, by their method of construction and general formation assume the nature of link blocks, although they are in effect sheathing bands 50 for the spring body structure, and are so termed to accord in terminology with the structure heretofore described. This post comprises end bands 21 to which are connected bands 22 connected in turn by a central band 23, although it is appreciated that any number of alternately arranged bands 22 and 23 could be employed. Each of the band blocks is provided with a series of channels 24 extending longitudinally with 55 respect to the posts as a whole and adapted to aline with the channels of the other band blocks for the reception of spring members 25, extending longitudinally through the posts and terminating, however, short of 60 the outer ends of the end links, to provide

clearance for pintle rod channels 26 formed therem. In the present instance three of these spring members are shown, in the form of spring rods, although a single strip, or a plurality of strips could as well be utilized, 70 these spring rods in the present instance forming the body of the post.

The adjacent edge portions of the link posts are rounded for mutual pivotal sliding engagement, as heretofore set out in 75 connection with the bands of the previous types of posts.

The structure shown in Figs. 5 and 6 are similar in many respects to the type of structure of Figs. 1 and 2 and there are provided end sheathing bands 27 corresponding to the end band members of this other type and provided with the usual pintle rod channels 27'. The body of this post comprises a spring strip 28 having its end portions bent inwardly and disposed in slideable lapped relation to form a loop having its end portions disposed within the end sheathing bands 27 and embracing an intermediate flexible filler body 29, the filler body 80 and loop ends being secured in the end bands 27 by rivets 30. Disposed about the body between the end sheathing bands are a series of sheathing bands 31 and the edge portions of these loops engage in abutting 85 relation. Thus to permit flexure of the posts with this type of sheathing loop it is necessary that the combined width of the loops be less than the distance between the end sheathing loops whereby the loops may 90 have longitudinal sliding movement on the body to compensate for their hinge movement upon flexure of the post.

In Figs. 7 and 8 a post is provided including end sheathing bands 31' receiving the ends of a body spring strip 32 and having solid outer head portions provided with the usual pintle rod channels 33. The intermediate sheathing band of this present structure is procured by a flattened coil 34 having its ends secured to the end sheathing bands. Thus each coil of the strip forms a 100 sheathing band for the spring body strip.

Although several embodiments of the invention have been described, it is apparent 115 that still other forms could be procured without departing in any manner from the spirit of the invention, which contemplates as heretofore stated, essentially the provision of a flexible binder post provided 120 with a metallic or similarly non-pliable sheathing, transversely hinge jointed to permit free flexure of the post, and to compensate for the essentially greater length of that side surface of the post which is disposed in a relatively large arc when the post is flexed.

I am aware that the provision of a metallic sheathing for flexible binder posts has been contemplated and Patent No. 1,056,926 130

granted to me March 25, 1913, embodies a structure affording a metallic sheathing of certain sorts. The structure of this post and of similar posts, however, includes merely 5 longitudinally extending side sheathing strips and affords no sheathing for the end portions of the post, and the exposed side edges of the longitudinal sheathing plates constitutes considerable inconvenience. Also 10 it is necessary in this type of structure to provide for a relatively longitudinal sliding movement of portions of the plates with respect to the body, which in commercial applications of the device entails a considerable 15 disadvantage.

I claim:

1. A flexible post comprising a body flexible in one plane only, and a transversely hinge-jointed sheathing for the body.
2. A flexible binder post comprising a longitudinal body flexible in one plane only and a series of hingedly connected transverse sheathing bands disposed thereabout.
3. A flexible binder post comprising end 25 transverse sheathing bands, intermediate transverse sheathing bands, a longitudinal resilient body flexible in one plane only, disposed within the bands and means connecting the bands in a manner permitting 30 relative pivotal movement thereof.
4. A flexible binder post comprising end transverse sheathing bands, intermediate

transverse sheathing bands, a longitudinal resilient body, flexible in one plane only, disposed within the bands and means independent of the resilient body for connecting the bands in a manner permitting relative pivotal movement. 35

5. A flexible binder post comprising a body flexible in one plane only, and a series 40 of hingedly connected transverse oblong sheathing bands disposed thereabout and having their end portions rounded for mutual pivotal sliding engagement.

6. A flexible binder post comprising a 45 body flexible in one plane only and a series of hingedly connected transverse sheathing bands disposed thereabout, with their side edges in lapped relation, and with their end edge portions rounded for mutual pivotal 50 sliding engagement.

7. A flexible binder post comprising a body including a resilient strip, pliable and slightly extensible strips at the sides of the resilient strip, sheathing bands disposed 55 about the ends of the strips and secured thereto, and a series of intermediate sheathing bands disposed about the body.

In testimony that I claim the foregoing I have hereunto set my hand at Milwaukee, 60 in the county of Milwaukee and State of Wisconsin.

HENRY C. MILLER.
